CLAIM

I claim the ornamental design for combination panels for horizontal wall mount rack, as shown and described.

DESCRIPTION

FIG. 1 is a front isometric view of the combination panels for horizontal wall mount rack according to our design;

FIG. 2 is a front isometric view shown in use;

FIG. 3 is a rear isometric view of the combination panels for horizontal wall mount rack shown in FIG. 1;

FIG. 4 is an isometric view of the combination panels for horizontal wall mount rack shown in use in FIG. 2;

FIG. 5 is a front elevation view of the combination panels for horizontal wall mount rack shown in FIG. 1;

FIG. 6 is rear elevation view thereof;

FIG. 7 is a top plan view thereof, with the opposite side being a mirror of that shown; and,

FIG. 8 is a side elevation view thereof, with the opposite side being a mirror of that shown.

The broken lines shown represent unclaimed rails and form no part of the claimed design.
